UNITED STATES PATENT OFFICE.

HARRY C. MAYES, OF PHILADELPHIA, PENNSYLVANIA

STRAW HOLDER AND DISPENSER.

No. 900,866.

Specification of Letters Patent.

Patented Oct. 13, 1908.

Application filed February 7, 1908. Serial No. 414,855.

To all whom it may concern:

Be it known that I, HARRY C. MAYES, citizen of the United States, residing at Philadelphia, in the county of Philadelphia and State of Pennsylvania, have invented certain new and useful Improvements in Straw Holders and Dispensers, of which the following is a specification.

This invention comprehends certain new and useful improvements in apparatus for holding and dispensing straws for use in connection with soda fountains and in other places where such articles are used, and the invention has for its primary object a simple and efficient apparatus of this character which will possess, to a marked degree, sanitary characteristics in that the straws cannot be handled by the customers before being ejected from the container for use and cannot be returned to the holder or container after being used, and in that the straws within the container are effectively protected from dust or other unhygienic conditions.

A further object of the invention is a simple, durable and efficient construction of device of this type which will occupy comparatively little space on either a counter or small table, and which may be operated from either side so as to drop one straw at a time upon a rack supported underneath the straw receptacle or container, said rack being accessible to the customer on either side of the apparatus, or, if desired particularly for counter use solely, the rack may be designed to carry the straw out to that side of the apparatus where the operator or attendant stands. And a further object of the invention is a straw holder and dispenser, the parts of which are so constructed and arranged that a single straw will be ejected at each operation, the straws being held in proper alinement at all times while in the container so as to be positively ejected at each and every operation, without any danger of being crushed or broken.

With these and other objects in view as will more fully appear as the description proceeds, the invention consists in certain constructions, arrangements and combinations of the parts that I shall hereinafter fully describe and then point out the novel features thereof in the appended claims.

For a full understanding of the invention, reference is to be had to the following description and accompanying drawings, in which:

Figure 1 is a perspective view of one form or embodiment of my invention; Fig. 2 is a top plan view thereof, with the cover removed and with a portion broken away to illustrate subjacent parts; Fig. 3 is a longitudinal sectional view of the apparatus; Fig. 4 is a transverse sectional view thereof; Figs. 5, 6 and 7 are detail sectional views in the nature of diagrams, illustrating the operations of the ejecting device; and, Fig. 8 is a detail fragmentary perspective view of the ejecting device.

Corresponding and like parts are referred to in the following description and indicated in all the views of the drawings by the same reference characters.

My improved straw holder and dispenser embodies a horizontally-disposed receptacle or container, the body portion 1 of which is preferably trough-shaped as shown and secured to the ends 2 that are provided with legs 3 by which the container may be held in a somewhat elevated position on a table, counter, or the like. Preferably, although not necessarily so, the body portion 1 is formed of sheet metal secured by screws or similar fastening devices, to inwardly facing marginal flanges 2^a of the ends 2. Said ends are formed at their upper corners with recesses 2^b in which a plate glass or metal lid or cover 4 fits, so as to render the container practically dust proof.

The body portion 1 of the straw container is formed at its bottom with a longitudinally extending opening 5, and below and spaced from such opening is a cut-off strip 6 which also extends longitudinally in alinement with the opening 5, said strip being secured at its ends in any desired way, to the ends 2 of the container, as best seen in Fig. 3. The open space between the cut-off strips 6 and the opening 5 provides two oppositely facing and longitudinally extending ejecting or discharge openings, as clearly illustrated in Fig. 4, and an ejecting device 7 is mounted to slide or oscillate in said space between the cut-off strip 6 and opening 5. The ejecting device 7 in the present embodiment of the invention is secured at its ends by rivets 8 to the lips 14 of the plates 13. The said cut-off device embodies two longitudinally extending bars that are spaced from each other as shown, to form a longitudinal pocket between them, the top of the pocket being designed to register with the opening 5 and being designed to receive a straw from the

container, and the bottom of the pocket being formed by the cut-off strip 6. As the ejecting device is swung from one side to the other, one straw at a time will drop into the 5 pocket 9 and be carried sidewise and discharged therefrom as soon as the space between the side bars of the ejecting device passes beyond one side edge of the cut-off strip. Each of these two side bars is formed 10 in its upper face with a relatively shallow longitudinally extending trough 10 defined along one side by a rib or ridge 11 and at its opposite, or outer side by a corresponding rib 12, the said ribs being arranged to accurately 15 fit against the outer surface of the body portion 1 of the container, so that no matter what position the ejecting device may be in, the two outermost ribs 12 will engage with said outer surface of the body portion 20 and effectively exclude dust from the interior thereof.

In order to assist in holding the ejecting device in proper longitudinal alignment with the discharge opening of the container, I 25 provide the plates 13 that are mounted within the ends of the container as best seen in Figs. 3 and 4 and that are formed with depending lips 14 entering the pocket 9 at the ends thereof (see Fig. 8). These plates 30 13 are mounted upon a longitudinally extending shaft 15, the ends of which are journaled in the ends 2 of the container. In order to swing the ejecting device, I provide in the present instance two pairs of 35 diverging curved arms 16 that are secured at their lower ends to the side bars of the cut-off as best seen in Fig. 4, and that carry at their upper ends, on both sides of the container, horizontal actuating rods 17, so that 40 if desired, the device can be actuated from either side. In order to automatically bring back the parts to normal position, after each operation, I may provide springs 18 secured in either one or both ends 2 of the container, 45 as shown in Fig. 4 and designed to bear upon a square block or blocks 19 secured to either one or both ends of the shaft 15, the tension of said spring or springs manifestly rocking the shaft 15 back to normal position and 50 maintaining the parts in a relatively stationary condition until it is desired to positively operate the device. In an apparatus of this character, it is important to prevent the straws or other articles that may be dis- 55 pensed from crowding together at the discharge opening, and for this purpose, I mount upon the shaft 15 a series of depending and transversely oscillating sector plates 20, the lower curved edges of which corre- 60 spond approximately to the cross sectional contour of the body portion 1 and are preferably spaced from the interior wall of such body portion a distance substantially equal to the diameter of the individual straws. By this means, it is manifest that

the straws will be held in a single row as they feed downwardly towards the discharge opening, the oscillation of the series of plates 20 raising a quantity of the straws at each operation, and the feed being thereby effect- 70 ively controlled.

As the straws are ejected from the container, they may be caught by a rack underneath the same. This rack may be of any desired construction or formation, according 75 to judgment or taste, or the particular conditions existing where the device is to be used. For instance, as illustrated in Fig. 1, the rack may comprise two inwardly extending and outwardly bowed frames 21, secured to the 80 legs 3. This particular construction is specially adapted for use on small tables where it is desired that the customer shall help himself to the straws by the normal actuation of the apparatus, when sitting or standing on 85 either side of the latter, this specific arrangement enabling the customer to pick up the straw from the rack upon either side of the container with equal facility. If the apparatus is to be used on a counter where an attendant alone is supposed to serve the straws, the rack frame may be formed, as illustrated in Fig. 4, designated 21^a, it being clear that by this specific construction of rack, the straws will be discharged at one side only of 95 the apparatus, where the attendant is standing.

In the practical operation of my improved straw holder and dispenser, the straws, as above described will be maintained in a 100 single row, underneath the feed controlling plates 20. Referring particularly to Figs. 5, 6 and 7, it will be seen that as the actuating rod 17 is depressed, one of the troughs 10 will be passed forwardly across the opening 5 and will engage a straw. The ridge 11 at the inner edge of the advancing trough will cause a straw to drop straight and roll straight into the trough 10, and as the rod is released and the ejecting device automatically swings back to its normal position, the side edge of the wall of the opening 5 in the body portion 1 of the container will engage the straws and roll one of them up over the ridge 11 of the ejecting device and thereby 110 cause a straw to drop squarely into the pocket, from which it will be discharged by the subsequent depression of the actuating rod.

From the foregoing description in connection with the accompanying drawings, it will be seen that I have provided a very simple and efficient construction of straw holding and dispensing apparatus which will be practically dust proof and otherwise sanitary in use and which will positively eject the straws without danger of mutilating the same, the main controlling devices preventing all crowding of the straws at the discharge opening and maintaining a uniform 130

feed while the inner ridges 11 of the ejecting device will properly distribute the straws at the discharge opening, to secure the proper alinement of the straws one at a time with 5 the pocket 9, the outer ribs of said ejecting device bearing against the exterior of the bottom of the body portion 1 and excluding dust from the interior thereof.

If desired, the arms 16 on one side of the 10 device may be formed out of sheet metal, all in one piece, with the corresponding side bar of the ejecting device, the other side bar and arms on the opposite side of the device being correspondingly formed.

15 Having thus described the invention, what is claimed as new is:

1. An apparatus of the character described, comprising a container formed in its bottom with an opening, a cut-off strip secured below and spaced from said opening and providing therewith two oppositely facing discharge openings, an ejecting device adapted to slide laterally in the space between said cut-off strip and the opening in the bottom 20 of the container, a support for said cut-off device, and actuating rods secured on opposite sides of the container and having connection with said ejecting device.

2. In an apparatus of the character described, the combination of a container provided with a discharge opening, an ejecting device arranged to move across said opening, a support for said ejecting device, the ejecting device being formed with a pocket 35 adapted to register with said opening and with a trough at one side of said pocket, and means for moving said ejecting device.

3. In an apparatus of the character described, the combination of a container provided with a discharge opening, an ejecting device arranged to move across said opening, a support for said ejecting device, the ejecting device being formed with a pocket 45 adapted to register with said opening and alongside said pocket with a trough, ribs defining the sides of the trough, and means for moving said ejecting device.

4. In an apparatus of the character described, the combination of a container provided with a discharge opening, an ejecting 50

device adapted to move back and forth across said opening, a support for said ejecting device, the ejecting device being formed with a pocket adapted to register with the said opening and on both sides of said pocket 55 with longitudinally extending troughs and inner and outer ribs defining the sides of said troughs.

5. In an apparatus of the character described, the combination of a container provided with a discharge opening, an ejecting device adapted to move back and forth across said opening, a support for said ejecting device, the ejecting device being formed with a pocket adapted to register with the said 60 opening and on both sides of said pocket with longitudinally extending troughs and inner and outer ribs defining the sides of said troughs, the outermost ribs bearing against the exterior wall of the container.

6. An apparatus of the character described, comprising a container provided with a discharge opening, an ejecting device adapted to move across said opening and eject articles therethrough, a shaft supported within the container, plates 13 secured to the shaft near the ends thereof, and formed with depending lips engaging said ejecting device, means for moving the ejecting device and plates, and means for automatically returning 75 the parts to normal position.

7. An apparatus of the character described, comprising a container provided with a discharge opening, and an ejecting device arranged to move across said opening and eject articles therethrough, a shaft mounted in said container, plates secured to said shaft, and having connection with the ends of the ejecting device, a block secured on said shaft, a spring secured in said container and bearing upon said block with a tension to turn the shaft to normal position, and means for moving said ejecting device.

In testimony whereof I affix my signature in presence of two witnesses.
